UNITED STATES PATENT OFFICE.

AXEL HANSEN, OF COTTAGE GROVE, OREGON.

SHEARS.

1,104,495.

Specification of Letters Patent. Patented July 21, 1914.

Application filed February 11, 1914. Serial No. 817,899.

To all whom it may concern:

Be it known that I, AXEL HANSEN, a citizen of Norway, residing at Cottage Grove, in the county of Lane and State of Oregon, have invented certain new and useful Improvements in Shears, of which the following is a specification.

This invention relates to improvements in shears wherein the cutting operation is effected by a pair of levers, carried by the handle of the tool and serving to operate the blades.

The construction of the device is such as to facilitate the cutting operation as the operator has but to manually force the blades together by means of either of said levers and oppositely disposed springs connected to the stock and bearing upon the said blades will, when pressure is released from the levers, force the blades apart.

With the foregoing and other objects in view the invention consists in the combination and arrangement of parts to be herein-after fully described in the following specification, pointed out in the claims and illustrated in the accompanying drawing which forms a part of said specification and in which—

Figure 1 is a plan of my improved shears. Fig. 2 is a side elevation partly in section.

Like reference characters indicate corresponding parts throughout.

The reference numeral 1 indicates the stock which is formed hollow at each end. In the hollow forward end the blades 2, 3 are operatively secured upon a pivot 4 which extends through the stock and is embedded in each lateral wall of the same. The inner or non-cutting ends of the blades 2, 3 are adapted for engagement with a sliding cam 5 which is pivotally connected to a movable link 6 to which one end of a spring 7 is secured, the opposite end of said spring being connected as at 8 to the inner wall 45 of the stock.

9 is a lever pivotally disposed as at 10 in the stock and extending through an aperture 11 in the same to permit its engagement by the finger of the operator and said lever is pivoted at 12 to the link 6; 13 is a lever pivoted at 14 in the stock and projected through an aperture 15 in the same and it is pivotally connected at 16 to the link 6, and the upper or free end of the

lever 13 permits its engagement by the finger of the operator. The purpose of the levers 9 and 13 is to afford a means by which the link 6 may be manually thrust forward or toward the blades 2, 3 against the tension of the spring 7 thus forcing the cam 5 between the ends of the said blades and closing them at their cutting ends thus performing the cutting operation.

To opposite sides of the stock springs 17, 18 are secured which extend, respectively, through apertures 19, 20 in said stock and bear upon the non-cutting ends of the blades to force them apart after they have performed the cutting operation and pressure has been removed from the levers. It is readily seen that repeatedly pressing the blades together, by means of the levers, each time they are forced open by the oppositely disposed springs will perform a continuous cutting operation. To lock the blades shut a hook 21 is carried by the stock 1 and adapted for releasable engagement with the lever 9 when it is in the position shown in full lines in Fig. 2.

The end of the stock remote from the blades is of hollow formation and in this portion samples of fabric, needles, thimble etc. may be retained as clearly illustrated, and door 22, hinged at 23 to the stock may be provided to prevent accidental loss of such contents.

What is claimed is:—

1. In shears, a stock formed hollow at one end, cutting blades pivoted together within said stock, a sliding cam capable of mutual engagement with the inner ends of said blades, a spring secured to the inner wall of said stock, a link connecting said spring cam, a lever pivoted in said stock and projected therebeyond and secured at its inner termination to said link and oppositely disposed springs carried by said stock and projected thereinto for engagement with said cutting blades, whereby their cutting edges are normally forced away from each other. 100

2. In shears, a stock, cutting blades pivoted together carried by said stock, means carried by said stock for normally forcing the cutting edges of said blades away from each other, a manually operable lever pivoted to said stock, a link pivoted to said lever, a cam carried by said link capable of engagement with the non-cutting ends of

said blades whereby the cutting edges of the same may be forced together and return means connecting said link and stock whereby the said lever is moved to normal position when pressure is removed therefrom.

In testimony that I claim the foregoing as my own I have hereto affixed my signature

ture in the presence of two subscribing witnesses.

AXEL HANSEN.
